Attorney

By

UNITED STATES PATENT OFFICE.

DANIEL J. MONIHAN, OF ERIE, PENNSYLVANIA, ASSIGNOR TO GRISWOLD MANUFACTURING COMPANY, OF ERIE, PENNSYLVANIA, A CORPORATION OF PENNSYLVANIA.

OVEN.

1,342,455.

Specification of Letters Patent.

Patented June 8, 1920.

Application filed November 25, 1918. Serial No. 263,967.

To all whom it may concern:

Be it known that I, DANIEL J. MONIHAN, a citizen of the United States, residing at Erie, in the county of Erie and State of Pennsylvania, have invented new and useful Improvements in Ovens, of which the following is a specification.

This invention relates to ovens and consists in certain improvements in the construction thereof as will be hereinafter fully described and pointed out in the claims.

The oven is particularly adapted for use with gas stoves and is designed to provide a more even distribution of the heat in the oven chamber than has heretofore been accomplished.

The invention is illustrated in the accompanying drawings as follows:—

Figure 1 is a front elevation of the oven, a part being broken away to better show construction.

Fig. 2 a vertical section in a plane from front to rear of the oven.

Fig. 3 a vertical section through an end flue of the oven.

1 marks the bottom plate of the oven chamber, 2 the side walls, 3 the back wall, 4 the bottom plate of the exterior shell, 5 the side walls of the exterior shell and 6 the top wall of the shell. The bottom plate has an opening 7 which is ordinarily set over a gas burner and this opening enters into a bottom flue, or chamber 8. The flue or chamber 8 communicates at its ends with a vertical flue 9 arranged between the side walls 2 and 5. The space between the walls 2 and 5 is closed at the top of the flue 9 by a plate 10 and openings 11 are arranged in the wall 2 in the oven chamber. A partition 12 divides the oven chamber into an upper and lower space. This partition is double-walled and a flue 12^a is formed between these walls. Openings 13 open from the flue 12^a into the bottom space and openings 14 connect the flue 12^a with the upper space of the oven. The gases pass from the upper space through openings 15 in the side walls and downwardly between the walls 2 and 5 in a flue 16 formed between said walls and discharge through openings 17 in the side wall above the plate 10.

This oven in a general way is similar

to the oven described in patents to George W. Graves, #1,126,753, Feb. 2, 1915, and #1,187,727 June 20, 1916. In the construction shown in said patents the partition carrying the flue has openings at one edge of the partition leading from the bottom space and openings at the opposite edge of the partition plate entering the upper space of the oven. The gases passing from the walls of the oven and thence entirely across the bottom space to the openings in the partition are very much obstructed when there is material in the oven and as a result the oven is not uniformly heated. By placing the openings 13 at the center and carrying the gases each way to the openings 14 the material in the oven does not obstruct the passage of gases to such an extent as to interfere with uniform heating of the oven space. Furthermore the passage of gases approximately equal distances from both side walls tends to give a more uniform heating.

It will further be noted that the openings 11 are in a series of rows and cover a large part of the side walls of the lower compartment of the oven chamber. This gives a more uniform distribution of heat at all times and when the oven is obstructed by material in the oven the openings permit of a circulation from any part that may be unobstructed.

What I claim as new is:—

1. An oven comprising an oven chamber; means for introducing hot gases to the chamber; and a partition separating the chamber into an upper and lower space, said partition being in the form of a flue with a centrally located opening into one space and an opening near the periphery of the partition into the other space.

2. An oven comprising an oven chamber; means for introducing hot gases to the chamber; and a partition separating the chamber into an upper and lower space, said partition being in the form of a flue with a centrally located opening into one space and an opening near the end of the partition into the other.

3. An oven comprising an oven chamber; means for introducing hot gases to the chamber; and a partition separating the chamber

into an upper and lower space, said partition being in the form of a flue with a centrally located opening into one space and openings at opposite edges of the partition into the other space.

4. An oven comprising an oven chamber; means for introducing hot gases to the chamber at the ends and into the lower space of the oven; and a partition separating the oven chamber into an upper and lower space, said partition being in the form of a flue with a centrally located opening into the lower space.

5. An oven comprising an oven chamber; means for introducing hot gases to the chamber at the ends and into the lower space of the oven; and a partition separating the oven chamber into an upper and lower space, said partition being in the form of a flue with a centrally located opening into the lower space and an opening near the end of the partition into the upper space.

6. An oven comprising an oven chamber; means for introducing hot gases to the chamber at the ends and into the lower space of the oven; and a partition separating the oven into an upper and lower space, said partition being in the form of a flue with centrally located openings leading into the

lower space and openings leading from the 30 flue near its ends into the upper space.

7. An oven comprising an oven chamber; a partition separating the chamber into an upper and lower space, said partition being in the form of a flue with a centrally located 35 opening leading from the lower space of the chamber and discharging to the upper space; and means for introducing hot gases from the side walls of the lower space of the chamber.

8. An oven comprising an oven chamber; a partition separating the oven into an upper and lower space, said partition having a passage therein for the passage of gases from the lower space to the upper space; and 45 means for introducing gases to the lower space of the chamber, said means comprising openings through opposed walls of the chamber and said openings arranged and proportioned to distribute the gases as introduced to the oven over a major portion of said opposed walls, the entrance to the passage in the partition being remote from the opposed walls.

In testimony whereof I have hereunto set 55 my hand.

DANIEL J. MONIHAN.
